LOCKING DEVICE FOR COLD STORAGE VAULT DOORS

Carlos M. Welshons, San Francisco, Calif.

Application October 8, 1951, Serial No. 250,590

1 Claim. (Cl. 70—134)

1

The invention relates to cold storage vaults and more particularly to a novel arrangement for locking the door affording access to the vault.

In present day practice the door leading to the vault is usually locked by providing hasps on the door and adjacent wall portion and applying a padlock thereto. This method, however, is objectionable since a person locking the door may overlook the possibility of someone still remaining in the vault who then will be locked in the vault without any chance of egress.

It is therefore an object of the invention to provide locking means for a cold storage door whereby the door may be opened from the inside as well as the outside to prevent a person from being trapped in the vault.

It is another object to provide a lock actuating means for a vault door removed from the cold area so as to prevent freezing thereof.

A further object constitutes the provision of insulating or packing material around the cylinder of the lock to effectively obviate freezing thereof.

An additional object constitutes the provision of the key actuatable part of a door lock in a wall removed from the door opening, which lock is adapted to secure the door in closed position and to be opened from the outside as well as the inside of the vault.

It is also an object to provide certain features of construction of parts and arrangement thereof tending to increase the utility and efficiency of a device of the character specified.

With these and other objects in view which will become apparent from the disclosure of the invention, the latter comprises the means described in the specification, particularly pointed out in the claims and illustrated in the accompanying drawings, in which:

Fig. 1 is a perspective view of a cold storage vault in which the invention is incorporated.

Fig. 2 is an enlarged fragmentary section on the line 2—2 of Fig. 1.

Fig. 3 is an enlarged fragmentary section on the line 3—3 of Fig. 2.

Fig. 4 is a section on the line 4—4 of Fig. 3.

Fig. 5 is a section on the line 5—5 of Fig. 3.

Fig. 6 is a section on the line 6—6 of Fig. 3; and

Fig. 7 is a section on the line 7—7 of Fig. 6.

Referring to the various views of the drawings, 10 generally indicates a cold storage vault provided with a door opening 11 (Fig. 3) and a door 12 mounted on hinges 13 and manipulated by a handle 14. The wall 15 of the vault is constructed of sidings 16, 17, and 18 and the interior

2

of the wall is filled with granular insulation material 19. A sponge rubber strip 20 on the wall 15 is contacted by the door when in closed position and forms sealtight closure.

5 To the inside of the door adjacent the free edge thereof is secured a strap 21 by screws 22 (Fig. 6) and is provided with apertured flanges 23 and 24 (Fig. 7) to receive therebetween a tubular casing 25 which is held in position by a square pintle 26 whose ends protruding beyond the flanges are headed over. A spring 27 is secured at one end 28 to the casing 25 and is coiled around the pintle 26.

A strap 29 extends from the casing 25 a short distance and has secured thereto a bar 30 by rivets 31.

The bar 30 adjacent the free end is provided with an aperture 32 constituting a socket and its terminal portion is bent as at 33 to facilitate 20 turning of the bar about the pintle when so desired.

The siding 17 is cut away as at 34 and a strap 35 is secured to the siding 17 by screws 36 and is bent over as at 37 (Fig. 3) to contact the outer edge of said siding. Similarly the bar 30 is bent over as at 38 to ride on the bent over portion 37 of the strap 35. By this structure, when bar 30 is swung to the left (as seen in Fig. 3) the ends 37, 38 will apply a leverage to the door to swing it open, and the inherent resiliency of the strap 35 will enable it to be restored to its present position when the door is closed.

The wall 15 is formed with a horizontal through-bore 39 a short distance from the free door edge to receive the key receiving part of the locking elements for the door. A cylinder lock 40 is inserted from the outside of wall 15 into the through-hole 39 until the face plate 41 bears on a washer 42 which surrounds the edge of the hole 39. The cylinder 43 in standard locks has apertured lugs 44 (Fig. 4) to receive the threaded ends of screws 45. A plastic tubular casing 46 surrounds the cylinder and provides a space 47 that is adapted to be filled with low temperature 40 grease to form an air seal.

A plastic adapter 48 forms an extension of the casing 46 and has a reduced end 49 which enters the bore of the casing 46. The adapter 48 has two holes 50 which are reduced in diameter toward the lock cylinder to retain the screwheads in said adapter.

A tube 51 of plastic material forms the continuation of the adapter 48 and surrounds the reduced end 52 of said adapter.

55 Similarly a plastic adapter 53 forms the con-

tinuation of the tube 51 and enters the bore of the tube with a reduced end 54.

The adapters 48 and 53 are provided with three bores 55, 56, and 57 (Fig. 5). The bores 55 and 56 are in horizontal alignment, with the screws 45 and each receives a wooden tie-rod 58 which stops short of the screw 45.

A transverse bore 59 extends through the adapter 48 and forms a groove in the tie-rods 58 permitting the introduction of a dowel pin 10 60 to secure the tie-rods to the adapter.

Similarly the adapter 53 receives the other ends of the tie-rods 58 which are secured to the adapter by the dowel pin 61.

It is evident that the lock 40, casing 46, adapter 15 48, tube 51, and adapter 53 when assembled form a unitary structure.

A night latch 62 of standard construction is installed at the inside of the wall 15 and is retained in position by screws 63 which enter the 20 adapter 53.

The connecting bar connecting the lock and the night latch is in three aligned sections in which the end sections are bars 64, 64' respectively at the lock and night latch and the central section is a wooden bar 65 into which the ends of the bars 64, 64' extend so that upon turning of the key the night latch is actuated. The night latch 62 is mounted on an end plate 66 and has of course the standard latch bar 67 to which is 25 brazed or secured in any other approved or desired manner a bolt 68 which extends through a hole 69 in the wall siding 17 constituting a guide to enter the aperture 32 in bar 30 when the door is in closed position to keep it locked. If desired any other guiding means may be employed for the bolt.

From the foregoing it is obvious that if by chance a person is trapped in the vault he can open the door from the inside by manually swinging the end 33 of bar 30 out of locking engagement with the bolt 68.

In assembling the locking device, the adapters and the plastic tubing are put together by the tie-rods and dowel pins and inserted through the 45 hole 39 from the outside of wall 15 to extend about one-half inch from the inside of wall 15. Thereupon the end plate 66 is fastened to adapter

53 by the screws 63. Then the night latch is installed and bolt 68 is brazed to the latch bar 67.

In order to secure efficient locking means for the door without detrimental effects by low temperature the distance of the lock in the wall from the door opening is an important factor. It has been found that for a room having zero temperature the distance from the door opening should be equivalent to the insulating value of 6 inches of cork board and hence the lock should be installed six inches from the door opening if the insulation employed is cork board. If the insulating material is inferior to cork board in its heat insulating value, then the distance would be greater and if the material has better heat insulating properties, than cork board, then the distance would be less. The heat insulating property of cork board is employed in the trade as a standard measure.

I claim:

For use with a locking device comprising a lock and a night latch operatively connected by a connecting rod, a casing for said lock, an adapter secured to the lock and forming an extension of said casing, a tube forming a continuation of said adapter, and a second adapter forming an extension of said tube and having the night latch secured thereto, said casing, tube and adapters being made of thermal non-conducting material.

CARLOS M. WELSHONS.
